UNITED STATES PATENT OFFICE.

JOSEPH J. BERNIER, OF CHARTLEY, MASSACHUSETTS.

SEPARABLE CUFF-BUTTON.

1,339,314.

Specification of Letters Patent.

Patented May 4, 1920.

Application filed February 7, 1920. Serial No. 357,025.

To all whom it may concern:

Be it known that I, JOSEPH J. BERNIER, a citizen of the United States, residing at Chartley, in the county of Bristol and State 5 of Massachusetts, have invented certain new and useful Improvements in Separable Cuff-Buttons, of which the following is a specification.

My invention relates to cuff buttons or 10 fasteners of the pull apart type, and has for its essential objects inexpensiveness of construction; security against accidental separation of constituent parts; and strength.

To the above ends essentially my invention 15 consists in such parts and in such combinations of parts as fall within the scope of the appended claims.

In the accompanying drawings which form a part of this specification—

20 Figures 1 and 2 are plan elevations of the blanks from which are formed the entering and receiving members respectively of my cuff button or fastener,

Fig. 3, a longitudinal central section of 25 both members of the device in engaged position,

Fig. 4, a detail plan of the entering member,

Fig. 5, a like plan of the receiving member, and

Fig. 6, a side elevation, partially in central longitudinal section, of a modified form of my device.

Like reference characters indicate like 35 parts throughout the views.

My novel structure comprises two separable interengaging elements herein referred to as the entering member and the receiving member.

40 In forming the entering member a blank, such as that shown in Fig. 1, is by suitable tools cut from a sheet metal strip, comprising a disk 9 having peripheral arms 10 in alignment with each other, upon whose outer ends are semicircular sections or segments 11 having their plane edges at the extremities of the blank. Centrally of the edges project fingers or necks 12 terminating in circular portions 13 bent up by suitable tools into cups or hemispherical hollow heads either simultaneously with the cutting operation or subsequently.

45 The described blank is next bent into the form shown in Fig. 4 comprising a base or head 9 from which rise inwardly curved, 50 oppositely disposed, arms 10 integral with

the curved portions of the inturned sections 11. The two sections 11 lie in a common plane parallel with the portion 9 and constitute an abutment. The plane edges of the sections 11 are in this instance slightly spaced from each other. The fingers 12 and heads 13 are parallel with each other at right angles to the abutment.

55 The receiving member is formed from the blank shown in Fig. 2, cut from a strip of thin metal, comprising a central disk 15 provided with a central circular opening 16, and having oppositely disposed arms 17 merging into the peripheral portions of 60 semicircular sections 18 of greater width than the diameter of the portion 15. This blank is bent up as shown in Fig. 5 with the disk forming an abutment supported by peripheral inwardly curved arms 17 rising 65 from the curved edges of the inwardly directed sections 18 whose plane edges abut each other as at 19 and together constitute the head or base of the member.

70 The diameter of the opening 16 is sufficient to permit passage therethrough of the members 13, when the latter are compressed, by virtue of the resilient fingers 12. After such passage the fingers expand to normal 75 position making the diameter of the members 13 so positioned greater than the diameter of the opening 16. This form of interengagement allows relative oscillatory or 80 two direction movement of both button members.

85 The margins of the cuff button holes are afforded retaining seats by the concaved arms 10 and 17 intermediate the larger members 9 and 11, and 18 and 15 respectively.

90 It will be observed that the members 13 are nowhere in contact with any portion 95 of the receiving member except the abutment 15. This fact insures a maximum expansion of the fingers 12 after interengagement of the button parts and thus diminishes the 100 chance of accidental disengagement of the engaged parts.

105 It will be further noted that the described structure adapts itself to a single piece construction of each button member and a resultant saving in labor and expense of construction.

110 In the construction shown in Figs. 3 to 5 inclusive a complete button is shown, the members 9 and 18 forming the ornamental heads. Further opportunity for ornamentation is afforded, if desired, by applying in

any convenient manner face plates. Such a construction is shown in Fig. 6 wherein a plate 21 on the face of head 9 has an annular flange 22 surrounding the latter, with its edge 23 beaded over the same. A like plate 25 on the head 18, with a flange 26 has a bead 27.

I claim:—

1. In a cuff fastener, an entering member comprising a head, an abutment, arms uniting the head and abutment, spaced compressible fingers on the abutment, and heads on the fingers, and a receiving member comprising a head, an abutment, and arms uniting the last mentioned head and second abutment, the second abutment being provided with an opening adapted to admit passage therethrough of the heads upon the fingers when the fingers are compressed.
2. In a cuff fastener, an entering member comprising a head, an abutment, concave arms uniting the margins of the head and abutment, compressible resilient fingers on the abutment, curved heads on the fingers, and a receiving member comprising a head, an abutment, and concave marginal arms uniting the second head and the second abutment, the second abutment being provided with an opening adapted to admit the

curved heads therethrough when the fingers are compressed.

3. In a cuff fastener, an entering member comprising in a single piece of sheet metal a head, marginal arms upon the head, inwardly directed semicircular abutment sections on the heads having their plane edges spaced from each other, compressible resilient fingers on said edges, hollow semi-spherical heads on the fingers, and a receiving member provided with an opening sufficiently ample to admit the hollow heads only when the fingers are compressed.

4. In a cuff fastener, a receiving member comprising in a single piece of sheet metal an abutment provided with a central opening, concave marginal arms on the abutment, inturned semi-circular head sections on the arms provided with abutting plane edges, and an entering member comprising a head, and abutment, arms connecting the last head and the last abutment, compressible fingers on the last abutment, and heads on the fingers movable through the opening only when the fingers are compressed.

In testimony whereof I have affixed my signature.

JOSEPH J. BERNIER.
